Application June 17, 1941, Serial No. 398,396

5 Claims. (Cl. 101—93)

This invention relates to printing machines of the record card controlled type in which reciprocating type bars are employed.

The object of the invention is to improve the operation of the type bar mechanism so that higher operating speeds may be attained without sacrifice of any of the desirable features of former mechanism.

The type of construction to which the present invention is applied is what is known as an "alphabetical type carrier" used in electrically controlled accounting machines. Such carrier is composed of three parts, i. e. the principal carrier, type head, and zoning element, the zoning element and type head being individually and resiliently mounted on the principal carrier. The main carrier is moved upwardly toward printing position and is differentially stopped by an interposer to select a type for printing. Due to the resilient connection, the impact of stopping is transmitted to the type head and zoning element through a spring, and the type head and element upon stopping of the principal carrier effect a slight overthrow from which they recover before printing takes place. When the carrier is to be operated at much greater speeds than heretofore, the stopping impact of the principal carrier will be greater and overthrow of the type head results as before. With the arrangement of the present invention, an interconnection is provided between the principal carrier and the zoning element, whereby the overthrow of the zoning element will be restricted without interfering with the overthrow of the type head, which overthrow has a desirable cushioning effect.

Other objects of the invention will be pointed out in the following description and claims and illustrated in the accompanying drawing, which disclose, by way of example, the principle of the invention and the best mode, which has been contemplated, of applying that principle.

In the drawing:

Fig. 1 is a view of a type carrier assembly with parts of the controlling mechanism therefor shown.

Fig. 2 is an enlarged detail of the lower end of the assembly with the parts in relatively shifted positions.

Fig. 3 is a section taken along lines 3—3 of Fig. 2.

Fig. 4 is a view similar to Fig. 2 with the parts in different positions.

The type bar assembly is substantially the same as that shown in my Patent 2,016,682 granted

October 8, 1935. Its arrangement, therefore, will be briefly explained utilizing the reference characters in the patent for convenient cross reference.

5 The assembly comprises a main carrier 48 suitably mounted for vertical reciprocation. Its lower end is connected by a link 49 to an arm 47 which is pivoted at 46. A bail 45 oscillates about center 46 under control of the usual cams. Thus, as the bail 45 moves upwardly, a spring 50 rocks arm 47 clockwise to elevate the bar 48. On one edge of the bar are teeth 51 which successively pass the nose of the pawl 52 which is normally held out of the path of the teeth by a latch 53 which has a connection 54 with the armature 55 of magnet 21. The magnet 21 may be energized as any of the teeth 51 approach the pawl 52, thus releasing the pawl so that it engages a selected tooth and thereby prevents further upward movement of the carrier 48. Slidably supported on the carrier 48 is the zone bar 63 which is normally urged downwardly by a spring 66, pins 64 riding in suitable slots in carrier 48 and serving to guide the bar and block 67 riveted to the carrier acting as a limiting stop.

10 Abutting the upper end of bar 63 is the lower end 59 of the usual type head 29 which is also slidably mounted on the carrier 48 urged downwardly by the spring 60. By means of so-called 15 "zoning" mechanism, the zoning bar 63 is differentially positioned on the carrier 48 prior to the upward movement of the entire assembly. This differential positioning is effected through the cooperation of steps 70 in the lower part of bar 63 with a latch 69 pivoted on the main carrier 48. While the type bars are in elevated position, the zoning mechanism as fully explained in the patent operates to ultimately position an arm 95 (see Fig. 2) in one of three 20 positions as indicated. As the carrier is descending, a bail 124 is moved upwardly to its dot and dash line position and near the end of the downward stroke of the carrier the latch 69 strikes the bail and is rocked thereby in a clockwise direction out of engagement with the steps 70. Thereupon, the springs 66 and 60 move the member 63 and type head 29 downwardly on the carrier to their lowermost position with respect thereto. Following the restoration of the parts, mechanism is operated to move the arm 95 upwardly to one of its preselected three positions and in doing so it engages an extension 63a of the member 63 to move it upwardly on the carrier 48. Thereafter, bail 124 is moved downwardly 25 so that the latch 69 will rock into position to

engage one of the steps 70 to hold the member 63 and carrier 48 in their relatively displaced relationship which they retain when the bar now ascends.

The foregoing is substantially the manner of operation as set forth in greater detail in the patent referred to. For the purpose of the present invention, the extension 63a of member 63 has slidably mounted thereon a dog 200 supported by pins 201, 202 riveted to the extension. The pin 202 cooperates with a vertical slot in the dog 200 and the pin 201 cooperates with an oblique slot. The lower end of the dog is offset to extend under the extension 63a of member 63 as shown in Fig. 3, so that when the member 63 has descended, arm 95 is moved downwardly and it moves the dog 200 up against the extension 63a from the position of Fig. 4 to that of Fig. 2. This has the effect of rocking the dog about pin 202, so that a tooth thereon is withdrawn from notches 203 in the carrier 48. Fig. 2 shows the position of parts with the arm 95 in its highest position. As the bar rises from this position, the dog 200 under the influence of a wire spring 204 secured at one end to the extension 63a and at the other to the dog will rock into the uppermost notch 203. As shown in Fig. 4, the tooth on the dog fits loosely into the notch, that is, there is a clearance at both upper and lower edges of the tooth. The reason for this is as follows: In the upward movement of the type carrier at high speeds, the tripping of pawl 52 will effect a sudden interruption of carrier 48. The inertia of the type head 29 and the member 63 will, however, tend to cause these parts to continue their movement against the action of the springs 60 and 66, respectively. This overthrow is desirable in that it cushions the arresting action of the pawl 52, but it is also desired to control and limit the extent of such overthrow without interfering with the overthrow of the type head 29. This is taken care of by the relationship of the tooth and dog 200 with the notches 203.

Due to the clearance provided, the bar 63 may overthrow a slight amount sufficient to cushion the shock of stopping. Before the actual printing operation takes place, the parts will have rebounded to their original relationship with the parts in proper alignment for printing. It will be noted that the resilient connection between the carrier 48 and the type head 29 through spring 60, as well as the connection between the carrier and the zoning bar 63 through spring 66, makes for a smoother and quieter operation of the mechanism when the parts are restored by bail 45, that is, as the bail 45 rocks counterclockwise to bring carrier 48 downward, the carrier draws the bar 63 through the spring 66 and the type head through the spring 60. In

5 this case, the clearance provided above the tooth of the dog 200 allows a desirable amount of play so that the shock incident to picking up and retracting the type bar is cushioned by the springs up to the limit allowed by the clearance between the tooth and notch.

10 While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. 15 It is the intention therefore to be limited only as indicated by the scope of the following claims.

What is claimed is:

1. In combination, a type carrier, means for advancing and returning the carrier, a zoning element supported on the carrier, said element being positively advanced with the carrier, means for interrupting the movement of the carrier during its advance whereby at high speed the inertia of the element will tend to cause it to overthrow, and means interconnecting the element and carrier for limiting the amount of said overthrow.
- 20 2. The invention set forth in claim 1 in which means is provided for effecting a relative differential positioning of the zoning element and the carrier and in which the interconnecting means is effective to limit overthrow with the element and carrier in any relative position of 30 the two.
3. The invention set forth in claim 1 in which means is provided for disabling the interconnecting means when the carrier is in its returned position.
- 40 4. In combination, a type carrier, means for advancing and returning the carrier, an element mounted on the carrier for sliding movement in the direction of its travel, a latch on the carrier for urging the element therewith in advanced 45 direction, a spring interconnecting the element and carrier for urging the element with the carrier in return direction, means for interrupting the movement of the carrier during its advance whereby at high speed the inertia of the element 50 will tend to cause it to continue its advance against the action of said spring, and means interconnecting the element and carrier for limiting the amount of such continued advance.
5. The invention set forth in claim 4 in which 55 the interconnecting means comprises a toothed latch pivotally supported on said element with the tooth thereof entered into a notch in the carrier.

ALBERT W. MILLS.
